UNITED STATES PATENT OFFICE.

CHARLES LITTLEFIELD, OF VINALHAVEN, MAINE.

ROPE-CLAMP.

SPECIFICATION forming part of Letters Patent No. 278,155, dated May 22, 1883.

Application filed March 22, 1883. (No model.)

To all whom it may concern:

Be it known that I, CHARLES LITTLEFIELD, of Vinalhaven, Knox county, Maine, have invented a new and Improved Rope Holder or Clamp, of which the following is a full, clear, and exact description.

The object of my invention is to provide a cheap, efficient, and easily-applied and self-adjusting rope holder or clamp adapted for holding and splicing hempen or wire ropes without cutting, marring, or otherwise injuring the rope; and to this end my invention consists, principally, of two jaws or clamp-plates connected by links and pins, one of the pins passing through and working in an inclined slot formed upon the back of one of the jaws or plates.

The invention also consists in making one of the link-plates in the form of a hook, and adapting one of the pins to receive the hook, whereby when the plate is unhooked the holder is adapted to be placed sidewise upon the rope.

The invention also consists in forming diagonal or spiral rib or ribs upon the inner concaved face of one of the plates or jaws to correspond with the twists of the rope, whereby all slipping of the holder upon the rope or the rope in the holder is prevented.

Reference is to be had to the accompanying drawings, forming part of this specification, in which similar letters of reference indicate corresponding parts in all the figures.

Figure 1 is a side elevation of my invention as it appears when applied to the rope. Fig. 2 is a sectional elevation taken on the line xx of Fig. 1, and Fig. 3 is a similar view taken on the line yy of Fig. 2.

A and A' represent the clamp-plates or jaws of the device. The plate or jaw A is formed with the inclined slot B at its back, is provided with the ring C at one end, and is made slightly concave upon its inner face, as shown at D , Fig. 2. The plate or jaw A' is slightly concaved, and formed with the diagonal or spiral rib or ribs E upon its inner face, as shown in Fig. 3, and is attached to the plate or jaw A by means of the side links or plates, $F F'$, and bolts $G G'$, the latter of which passes through the inclined slot B , as shown in Figs. 1 and 2. The plate F' is made in the form of a hook, as shown in Fig. 1, so that it may be easily attached to and detached from the bolt

G' , and to facilitate the attachment of the hook to and its detachment from the bolt G' , I form this bolt with the head H , over which the hook passes, and with the outer head or flange, J , which confines the hook and prevents it from moving laterally off from the bolt.

In applying the device to a rope, the bolt G' is first moved down to the lowest end of the inclined slot B , and the rope passed either endwise or, by unhooking the plate F' , sidewise between the jaws or plates $A A'$, with the ring end of the device away from the direction of the strain that will be put upon the rope. The bolt G' is then moved up in the slot B as far as it will go, which will cause the plates $A A'$ to be drawn snugly upon the rope. Now, upon strain being applied to the device at the ring C , in the direction of the arrow, or to the rope, away from the arrow, the action of the inclined slot B upon the bolts and side plates will cause the jaws $A A'$ to grasp the rope with a firmness increasing with the strain, so that whatever the strain the device will securely hold the rope, and the clamp-plates being of considerable length and made to fit the rope, they will not cut or mar the rope, and the jaw A' being formed with rib or ribs $E E'$, which will engage with the coils of the rope, there is no danger of the rope slipping in the device. Besides, the device is cheap, durable, and easily attached to and detached from the rope, and is adapted for a variety of uses.

Having thus described my invention, I claim as new and desire to secure by Letters Patent—

1. The rope-holder herein shown and described, consisting of the connected jaws or plates $A A'$, the jaw A being formed with the inclined slot B , adapted to cause the jaws to grasp the rope, as set forth.

2. The jaw A' , formed with the diagonal rib or ribs E , in combination with the jaw A , inclined slot B , side plates, $F F'$, and bolts $G G'$, as and for the purposes set forth.

3. The combination, with the jaws $A A'$, plate F , bolts $G G'$, and inclined slot B , of the hooked plate F' , adapted to fit upon the double-headed bolt G' , substantially as and for the purposes set forth.

CHARLES LITTLEFIELD.
